(57) **CLAIM**

The ornamental design for a wheel cover, as shown and described.

DESCRIPTION

FIG. 1 is a top, right, front perspective view of a wheel cover showing our new design; and,

FIG. 2 is a right elevational view thereof.

The uniform broken line showing in FIGS. 1-2 is for the purpose of illustrating portions of the wheel cover and forms no part of the claimed design.

1 Claim, 2 Drawing SheetsFIG. 1

FIG. 2
